(54) **TIN PLATE, COATING WITH LEAD**

(76) Inventor: **Joseph M. Truman**

Joseph A. M. Grunman, of Philadelphia, Penn.

Letter's Patent.

The schedule referred to in these Letters Patent, and making part of the same, containing a description in the words of the said Joseph A. M. Grunman himself, of his improvement in the mode of rendering tin plate more durable by coating the same with lead.

To all whom it may concern:—Be it known that I, Joseph A. M. Grunman, of the City of Philadelphia, have invented a method of rendering tin plate more applicable to various uses than in the ordinary manner of applying it, with a simple coating of tin upon the iron and that the following is a full and exact description of my said invention.

The purpose I have in view is to procure the iron more effectually, form, cast, and consequently render the plate much more durable than heretofore when employed for the covering of roofs, the making of pipes, gutters, cisterns, bathing tubs and various other articles. In order to attain this end, I cover the tin plates with a coating of lead, by immersing them in a bath, of that metal in a state of fusion. For most purposes, I dip the plates singly into the bath after having dusted them with powdered resin or any other suitable flux, after which, I unite them together in the usual way.

When required for gutters I generally groove the sheets together so as to form strips of convenient length; these strips are then passed thro' the molten lead immediately from the bath, to cause the strips to pass between one or more pair of rollers, which rollers may be made of wood or of metal, covered with several folds of cotton cloth, or other yielding substance; these rollers being greased with oil or tallow.

I have thus described the mode in which I usually effect the proposed object—but I do not claim the particular implements or method employed, as making any part of my invention; what I do claim, and for which I ask a Patent, is the covering of the plate with a coating of lead and applying the plate, so coated to the purpose herein set forth.

Witness, New Haven, Joseph A. M. Grunman,
R. 13.
